Franklin & Powers.

UNITED STATES PATENT OFFICE.

FREDERICK HAILE, OF RADNOR, PENNSYLVANIA.

BREAKING BRIDLE.

Application filed January 12, 1924. Serial No. 685,845.

To all whom it may concern:

Be it known that I, FREDERICK HAILE, a citizen of the United States, residing in Radnor, Delaware County, Pennsylvania, have invented a Breaking Bridle, of which the following is a specification.

This invention relates to bridles adapted for breaking and working green horses, particularly saddle horses, polo ponies and 10 hunters.

The principal object of the invention is to provide a bridle which while eliminating the bit still affords perfect control.

Another object of the invention is to provide a bridle to which the green horse will respond more readily than to the ordinary forms of breaking bridle, particularly to that form of bridle which employs a bit, and which the horse will not instinctively fight 20 against, as they do bitted bridles.

A still further object of the invention is to provide a bridle which is incapable of injuring the mouth of a green horse in the breaking process.

25 A still further object of the invention is to provide a bridle which may be used as a dumb-jock.

The invention further resides in a novel construction and arrangement of elements 30 hereinafter described and illustrated in the attached drawings, in which:

Figure 1 illustrates the method in which the bridle is applied to the horse, and

Fig. 2 is a view in perspective of the novel 35 parts of the bridle.

With reference to the drawings, the bridle comprises a yoke 1 which fits over the nose of the horse, as clearly illustrated in Fig. 1 and which is provided at the bottom with a strap 2 which passes under the lower jaw of the horse and provides means for adjusting the yoke to the desired tension. The yoke 1, which is substantially U-shaped, is shaped to fit comfortably over the horse's 40 nose and is self-sustaining in the sense of being capable of maintaining without support the substantially U-shaped formation. This yoke may, for example, be made of a piece of light but comparatively rigid metal 45 bent to the required shape and covered with leather or other suitable covering material. The strap 2, which as clearly illustrated is attached to one end of the yoke 1, is preferably of leather or other flexible material and 50 may be secured to the other end of the yoke by means of a buckle 3, in the present in-

stance carried by the yoke. The strap 2 carries a roll 4 of horse hair or other suitable material which, as clearly illustrated, is adapted to fit into the chin groove of the 60 horse and which constitutes also spacing means for the ends of the reins 5, 5, which are looped over the strap 2. It will be apparent that the tightness of the strap 2 controls the pressure of the yoke 1 upon the 65 nose and the pressure of the roll 4 within the chin groove. The yoke 1 may be supported on the nose by means of the usual headstall comprising the two cheek pieces 6, 6, the crown piece 7, the front piece 8, 70 and the throat latch 9.

It will be apparent to those acquainted with the art that this bridle may be used as a dumb-jock in the stable by attaching the reins to the surcingle and tightening as 75 required. In breaking a colt or a green horse, the bridle should be used as a dumb-jock for a few days in a loose box or yard.

This bridle has been found extremely 80 practical and useful, particularly in breaking and working green saddle horses, polo ponies and hunters. Since it has no bit, it cannot injure the mouth, yet the horse is under perfect control and will not sulk or fuss, as a young horse is apt to do when a 85 bit is used. I have found that a young horse will rein back easier with this bridle than with a bitted bridle, this condition being due probably to the fact that with my bridle, the nose is pulled in and the neck 90 flexed more readily than when a bit is used. There is no tendency for a horse to fight this bridle, as there is where a bit is employed, and the horse will invariably respond readily and kindly to reining, backing, cantering from either lead, and changing leads in 95 figure 8, thus acquiring that perfect balance so essential to a riding horse.

In adjusting the bridle to the horse, the yoke should hang just above the nostrils 100 and should be fitted for the first day or so snugly. The pressure bears on the front of the nose and under the lower jaw, and by reason of the rigid nature of the yoke 1, or the manner of attaching the reins, it cannot 105 shut off the wind. As the horse becomes handy, the strap 2 may be loosened so that the bridle does not fit so snug.

I claim:

1. A bitless bridle comprising a self-sustaining yoke of inverted U-shape adapted to fit over the nose of a horse, fastening means

- for the yoke adapted to pass under the lower jaw and to be secured in fixed relation to the opposite ends of the yoke so as to form therewith a nose and jaw encircling part 5 whose perimeter remains constant in use, a headstall to support the yoke in position, and reins connected with the yoke.
2. A bitless bridle comprising a self-sustaining yoke of inverted U-shape adapted 10 to fit over the nose of a horse, a strap adapted to pass under the lower jaw and to be secured in fixed relation to the opposite ends of the yoke so as to form therewith a nose and jaw encircling part whose perimeter remains constant in use, a headstall 15 to support the yoke in position, and reins connected with the yoke.
3. A bitless bridle comprising a self-sustaining yoke of inverted U-shape adapted to 20 fit over the nose of a horse, fastening means for the yoke adapted to pass under the lower jaw and to be secured in fixed relation to the opposite ends of the yoke so as to form therewith a nose and jaw encircling part 25 whose perimeter remains constant in use, means providing for adjustment of the length of said fastening means, a headstall to support the yoke in position, and reins connected with the yoke.
- 30 4. A bitless bridle comprising a self-sustaining yoke of inverted U-shape adapted to fit over the nose of a horse, a flexible member permanently attached to one end of said yoke and adapted to pass under the lower jaw, means for detachably securing the flexible member in fixed relation to the other end of said yoke, a headstall to support the yoke in position, and reins connected with the yoke.
- 35 40 5. A bridle comprising a self-sustaining yoke of inverted U-shape adapted to fit over

the nose of a horse, fastening means secured to the lower ends of said yoke and adapted to pass under the lower jaw of the horse, and an element carried by said fastening means and adapted to project into the chin groove of the horse.

6. A bridle comprising a self-sustaining yoke of inverted U-shape adapted to fit over the nose of a horse, fastening means secured 50 to the lower ends of said yoke and adapted to pass under the lower jaw of the horse, an element carried by said fastening means and adapted to project into the chin groove of the horse, and reins attached to said 55 fastening means at opposite sides of said element.

7. A bridle comprising a member adapted to pass over the nose of a horse, means passing under the lower jaw of the horse 60 for securing said member in place, and an element carried by said securing means and adapted to project into the chin groove of the horse.

8. A bridle comprising a member adapted 65 to pass over the nose of a horse, means passing under the lower jaw of the horse for securing said member in place, an element carried by said securing means and adapted to project into the chin groove of 70 the horse, and reins attached to said securing means at opposite sides of said element.

9. A bridle comprising a member adapted to pass over the nose of a horse, means passing under the lower jaw of the horse 75 for securing said member in place, an element carried by the securing means and adapted to project into the chin groove of the horse, a headstall for supporting said member, and reins connected with said 80 member.

FREDERICK HAILE.
